UNITED STATES PATENT OFFICE.

ENOCH J. ROWE, ROBERT HOLMES, AND ERASTUS W. WELLS, OF EUREKA,
CALIFORNIA.

AMALGAMATOR.

SPECIFICATION forming part of Letters Patent No. 354,809, dated December 21, 1886.

Application filed August 10, 1885. Serial No. 174,014. (No model.)

To all whom it may concern:

Be it known that we, ENOCH J. ROWE, ROBERT HOLMES, and ERASTUS W. WELLS, citizens of the United States of America, residing at Eureka, in the county of Humboldt and State of California, have invented certain new and useful Improvements in Amalgamators, of which the following is a specification, reference being had therein to the accompanying drawings.

This invention pertains to improvements in amalgamators for treating refractory ores of various kinds, wherein the ore is subjected to a bath of molten lead, the same (the ore) being passed through the molten lead by means of an endless chain having at intervals carrying-plates upon which the ore is placed or carried, whereby are thrown off or rejected the rebellious or foreign matters—as, for instance, antimony, arsenic, zinc, &c.

To the said ends the invention therefore consists of the peculiar construction, combination, and arrangement of the parts, substantially as hereinafter described and claimed.

In the accompanying drawings, Figure 1 is a front elevation with the front wall removed, exposing the internal arrangement thereof in part. Fig. 2 is a sectional elevation of the same taken through it from front to back.

Fig. 3 is another front view. Fig. 4 is a side view of our improved smelting-furnace. Fig. 5 is a plan or top view thereof; and Fig. 6 is a plan view of the bottom of the receptacle.

In carrying out our invention we employ, preferably, an upright quadrangular receptacle or inclosure, A, having in one (the rear) side the combustion-chamber B, partitioned off from a second chamber, B', in the front side of the receptacle and extending from bottom to top thereof. The bottom of this chamber is inclined from the rear its entire width downward and forward a portion of the length thereof, and made V shape in cross-section the rest of its length, with the tapering portion or vertex having a coincident inclination with the rear part. Over this bottom is arranged a grate, a, with legs, one at each corner, resting upon horizontal marginal surfaces of bottom. Upon the top of the inclosure or receptacle A, in alignment with the chamber B, is

secured the chimney b. Two openings, a' a'', supplied with suitable doors, are made in the front side of the réceptacle, one communicating with the combustion-chamber low down, near the bottom, and the other with the same chamber farther up, about midway thereof.

Through the partition between the two chambers B B', at the bottom, are two openings, e, one being arranged at each side and closed by removable slides or doors e', having manipulating projections e''. These openings e permit the passage of the heat from the chamber B to the chamber B' to heat the latter, while by closing said openings, by their slides e', the heat can be cut off from the chamber B'.

Within the chamber B' is arranged a U-shaped receptacle or holder, C, for containing molten lead to about the depth indicated by the dotted line X X, Fig. 1, the said receptacle or holder being secured to the dividing-partition between the two chambers B B', with the bend or curved connecting portion of the legs disposed downward near the bottom of the chamber B'. The said curved portion or bend of the receptacle or holder C may be slightly extended, about centrally, at its lower side into a drain-trough, as at b', which is provided with a discharge spout or tube, b'', to permit the emptying of the receptacle or holder C of the molten lead, when desired; also in this bend or curved portion of the receptacle C, in its front side, is an opening, b³, for the removal of the ore after treatment, by which all rebellious matter—such as antimony, arsenic, zinc, &c.—is burned or thrown off from the ore undergoing treatment. This opening is closed from the inside by a plate or door, b⁴, held in position by a screw, b⁵, fixed thereto and passing through a yoke or bridge, b⁶, with its ends bearing and held against the outside of the receptacle C by a nut, b⁷, screwed upon said screw and against said yoke or bridge, which permits, by loosening the nut and lifting upon the screw, the elevating or opening of the door or plate b⁴, the latter being retained in its elevated or open position by screwing up the nut until the plate and yoke are clamped against the receptacle.

Before removing the treated or refined ore

from the receptacle or holder C through the opening b^3 , as above described, the molten lead or bath is drawn off through the spout or tube b^2 , after which the ore can be removed, as stated.

5 The upper ends of the legs of the receptacle C extend to within a short distance of the upper end of the chamber B', while one end is flared upwardly to facilitate the entrance of the ore, which is passed thereinto through a hopper, C', set into the top of the receptacle A, its tubular portion projecting below the said top a short distance into the chamber B', in alignment with said flared leg of receptacle.

10 D is an endless chain belt, with every other link provided with a disk or plate, D', which serve to hold or carry the ore as it is passed into the receptacle C by said chain being arranged to move within and through the said receptacle, its relatively upper portion passing over a sprocket-wheel, E. The wheel E is fixed to and carried by a shaft, d^2 , with the end to which the wheel is fixed extending into the chamber B'. The projections of the wheel E are deflected from opposite edges thereof at short intervals apart throughout the periphery, forming substantially a V-shaped groove around the periphery for the reception of the belt D. The shaft d^2 is supported in boxes d^3 , fastened upon brackets or legs secured upon a frame, F, with one end hinged upon one side bar of a frame, G, fastened by its angular inner longitudinal plate or bar, G', and plate-brackets G' to the front of the receptacle A, the upper outer ends of the brackets being connected to the outer longitudinal bar or plate of the frame G. The opposite free end of the frame F rests upon and is adjustably connected by screw-bolts e, or other suitable means, to the coincident end bar of the frame G. The shaft-supporting frame F is thus adapted by screwing up the screws e to be so adjusted as to tighten the chain D; or by unscrewing the screws e the chain may be loosened, as may be desired. Upon the outer end of the shaft d^2 is a pulley, which in practice is driven by a belt connecting with any suitable motor, whereby the endless chain D, with the disks or plates D', is put in motion, carrying or passing the ore through the molten lead in the receptacle C, thus treating or refining the same by reason of the antimony, arsenic, zinc, or other rebellious or foreign matter being thrown off or rejected therefrom.

15 In the front side of the receptacle A are two openings, d^2 , closed by suitable doors, g g, the larger one being arranged opposite the discharge tube or spout b^2 , while the upper smaller one is arranged in alignment with an opening, h, in the partition between the chambers B B', the heat and gases evolved from the fire in the combustion-chamber passing through said opening h and a larger opening 20 immediately above the same into the chamber containing the U-shaped receptacle or holder.

It will be observed that by means of the door-closed openings in one side and the front walls of the upper and lower portions of the containing receptacle, and the opening in the partition between the combustion-chamber and the chamber containing the molten-lead receptacle, the heat can be perfectly regulated, to insure the successful carrying out of the smelting process.

75

From the foregoing it will be seen that by means of the fire contained in the combustion-chamber the bath of molten lead contained in the U-shaped receptacle or holder will be kept at a proper temperature by the heat radiated and the gases evolved from the fire in said combustion-chamber, and pass off through openings in the partition-wall and mingle with the products of combustion.

80

A sufficient quantity of refractory ore is passed through the hopper in the top of the receptacle and thence into the longer flared leg of the receptacle or holder, and the sprocket-wheel being in motion by reason of the revolution of its shaft and pulley, (motion being derived through a belt passed over said pulley and connecting with a suitable motor,) the ore will, through means of the endless chain-belt, be subjected to the bath until all rebellious or foreign matters are removed therefrom, at which time the molten lead or bath is drawn off through the spout or tube b^2 , after which the treated ore is removed through the opening b^3 in the lower curved end of the receptacle C, as before stated.

95

100 The above-described operation may be repeated as often as may be desired, the molten lead or bath being placed to about the depth indicated in the U-shaped receptacle or holder, and after the ore has received sufficient treatment the same is withdrawn from said receptacle, as is also the treated ore, as before stated.

105

Having thus fully described our invention, what we claim, and desire to secure by Letters Patent, is—

110

1. In an amalgamator, the combustion-chamber having its bottom inclined downward and forward at the rear end its entire width a short distance and V-shaped in cross-section the rest of its length, and coincidentally inclined at the vertex with the rear part, substantially as shown and described.

115

2. In an amalgamator, the receptacle having the combustion-chamber and an additional chamber with the dividing-partition provided with door or plate covered openings at the bottom, in combination with the U-shaped receptacle or bath, substantially as and for the purpose set forth.

120

3. In an amalgamator, the combination, with the endless chain having a series of plates or disks and the U-shaped molten-lead receptacle, of the shaft carrying a sprocket-wheel, over which said chain passes, and the shaft-supporting frame hinged at one end and provided with adjusting screw-bolts at the oppo-

125

130

site end, substantially as and for the purpose set forth.

4. In an amalgamator, the combination, with the containing-receptacle, of the U-shaped molten-lead receptacle having the ore-removing opening closed from the inside by a plate or door having a fixed screw passing through a yoke or bridge and provided with a tightening-nut, said yoke or bridge bearing against the outside of the molten-lead receptacle, substantially as and for the purpose set forth.

5. An amalgamator comprising the containing-receptacle subdivided into two compartments, with their partition provided with slide-covered openings at the bottom, one compartment or chamber serving as a combustion-chamber, the U-shaped molten-lead receptacle or bath contained in one of the said compartments, and the sprocket-wheel and its shaft and pulley, one side wall and the front wall of said containing-receptacle having up-

per and lower door-covered openings, one opening in the front wall being arranged in alignment with an opening in the aforesaid partition, substantially as and for the purpose set forth. 25

6. In an amalgamator, the combination, with the sprocket-wheel, its shaft and pulley, and the endless chain or belt, of the shaft-supporting frame hinged at one end to a bracket secured to the receptacle and provided with adjusting screw-bolts at the opposite end, substantially as shown, and for the purpose stated. 30

In testimony whereof we affix our signatures in presence of two witnesses.
